WATER GATE

Filed Nov. 19, 1930

WILLIAM H. COGLEY
INVENTOR

BY *Herbert L. Smith*
ATTORNEY

UNITED STATES PATENT OFFICE

WILLIAM H. COGLEY, OF GREENACRES, WASHINGTON

WATER GATE

Application filed November 19, 1930. Serial No. 496,663.

My present invention relates to improvements in water gates of the removable type, employed in hydraulic and earth engineering and especially designed for use in irrigation ditches. The primary object of my invention is the provision of a water gate of this character, which is simple in construction and may be manufactured at comparatively low cost of production, and which is rugged and durable in order that it may withstand the rigorous treatment usually accorded such devices. By the special construction of the water gate of my invention, the gate may be shoved or forced by hand into the earth transversely of the ditch for damming the water in the ditch, and the gate may with equal facility be removed by hand from the ditch, when not required.

The invention consists essentially in a water gate that is capable of being located and employed effectively in any one of several sizes of ditches, with or without the use of auxiliary gates or valves, and such employment may be accomplished without change in the structure of the gate. The invention further consists in certain novel combinations and arrangements of parts as will hereinafter be more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a face view of a gate embodying my invention showing it in position for use with a ditch of small transverse area.

Figure 2 is a cross section on line 2—2 of Figure 1.

Figure 3 is a perspective view showing the gate in a large size ditch, and with the auxiliary gates or valves in use.

Figure 4 is a perspective view showing the gate in use in a medium size ditch.

Figure 5 is a perspective view showing the gate in use in a small size ditch.

Figure 6 is a face view of one of the aux-

iliary gates or slide valves, showing it closed in full lines and open in dotted lines.

Figure 7 is a vertical sectional view at line 7—7 of Figure 6.

Figure 8 is a top edge view of one of the auxiliary gates or slide valves.

Figure 9 is a face view of one of the auxiliary gates or slide valves.

In the preferred form of my invention as shown in Figure 1, the water gate is fashioned in egg or oval shape, from a sheet of galvanized iron, and has a maximum head 1, a minimum head 2, and two intermediate heads 3 and 4, any one of which may be used transversely of a ditch corresponding in size to the complementary head of the gate, as indicated in Figures 3, 4, and 5. The removable gate is shoved or pushed by hand into the earth or soil transversely of the ditch as indicated and forms a complete barrier for damming the water in the ditch.

A reinforcing rib 5 is pressed or otherwise formed in the metal of the gate and extends longitudinally along the longer axis thereof to add rigidity and strength to the metal plate or sheet, and to preserve its original form, and a reinforcing strap 6 is riveted along the shorter axis of the plate or sheet for the same purpose. In addition, the reinforcing strap projects at one side of the gate for use as a handle, and at the extremity of the handle a hook 7 is provided so that the gate when not in use may be suspended or hung from a support, as the limb of a tree.

If desired the head 4 may be shoved into the soil transversely of the ditch to form a "blind" gate, or the gate may be manipulated by the use of the handle or hooked end 7 and shoved into the soil with the medium head 1 in use in a ditch, with the smallest head 2, or with the other large head 3 in use, depending upon the position of the gate, as indicated in Figures 4, 5, and 3 respectively.

At one side of its long axis the gate is provided with a pair of auxiliary gates or valves 8 and 9, adapted to slide and uncover or partly uncover the openings 15 in the gate, in order that a limited quantity of water may pass through the gate while the

major portion is being dammed by the gate.

By disposing both gates or valves 8 and 9 at the same side of the longitudinal or long axis of the gate, both valves are capable of use, as in Figure 3, or valve 8 may be used as in Figure 4, or valve 9 may be used as in Figure 5, thus adapting the water gate and providing a complete device for any one of three sizes of ditches.

Each slide valve or auxiliary gate is provided with a curled top as 10 to form a handle, and at opposite sides of edges of the valve are provided projecting lugs 11. The valves slide across the openings 15 in the gate proper and are held in adjusted position by frictional contact with the face of the gate and with spaced guide plates 12 secured to the gate and formed with guide grooves 13 for the lateral edges of the slide valves. These grooved guide plates are fashioned with stops or abutments 14 and 14' near their lower and upper ends and these abutments co-act with the lugs 11 on the slide valves to prevent displacement of the valve and limit their range of movement. The slide valves are adjusted of course to vary the size of the opening 15 for controlling or regulating the passage of water through these auxiliary gates.

The water gate as herein described and illustrated is well adapted for various sizes, as main channels, laterals, and other ditches used in irrigation processes, and it will be apparent that a farmer equipped with a set of the water gates may with facility proceed to arrange for the disposition or distribution of water in the ditches and laterals, by placing the gates in their proper positions and locations for accomplishing the desired results.

Having thus fully described my invention, what I claim as new and desire to secure by Letters Patent is:

A sheet-metal water gate of oval shape having a reinforcing rib integral therewith and a transversely disposed handle strap, said gate having a small head at one end of its longitudinal axis, a larger medium head at the opposite end of its longitudinal axis, said heads together forming a larger head at one side of the longitudinal axis, and valved openings at one side of the longitudinal axis located in the small and medium heads respectively.

In testimony whereof I affix my signature.
WILLIAM H. COGLEY.
